UNITED STATES PATENT OFFICE.

JOHN H. MANNY, OF ROCKFORD, ILLINOIS.

IMPROVEMENT IN GUARD-FINGERS FOR HARVESTERS.

Specification forming part of Letters Patent No. 13,150, dated June 26, 1855.

To all whom it may concern:

Be it known that I, JOHN H. MANNY, of Rockford, in the county of Winnebago and State of Illinois, have invented certain new and useful Improvements in the Guard-Fingers of Reaping and Mowing Machines, of which the following is a full, clear, and exact description, reference being had to the accompanying drawings, of which—

Figure 1 is an isometrical representation of a part of the finger-bar of a mowing-machine having three fingers attached to it. Fig. 2 is a like representation of the same parts inverted. Fig. 3 represents a plan of the same parts seen on the under side. Fig. 4 is an isometrical representation of one of the fingers detached from the finger-bar, the cap of the finger being removed and shown in an inverted position in Fig. 5, while a modified form of this cap without a shank is shown in Fig. 6; and Fig. 7 represents a section at the line $x x$ of Fig. 1.

My invention consists in placing the neck of the lower part of the guard-finger obliquely to the direction in which the finger points, by which arrangement the tendency of grass, &c., to lodge is diminished.

I make the caps of the guard-fingers concave, the axis of the concavity being in the direction of the length of the finger, and the arch rising and widening toward the rear of the cap, to cause grass or other obstructions that may enter beneath the cap to pass backward and be discharged before a sufficient quantity can accumulate to wedge in tightly and clog the sickle.

I form the transverse ribs across the front portion of the shank of the finger whose ends are oblique, so as to form an acute angle at the front corner, which will act as a scraper or knife to detach grass, grain, &c., that may be hanging over the back of the sickle-stock, while the front side of these ribs will furnish a bearing for the back of the stock to work against, these ribs being interrupted by the removal of a section out of the middle to form a gap which widens toward the bottom to facilitate the discharge of gum, grass, &c., that may be detached from the sickle and enter these spaces.

In the accompanying drawings, A represents

the finger-bar, which may be made of the usual or of any convenient size and material.

B is the lower part of the guard-finger, which is seen detached in Fig. 4. The front part or point *a* of this finger is represented of the improved form described in my former patents, and is connected to the shank *b*, by which the finger is attached to the finger-bar by means of an oblique neck, *c*, of sufficient strength to support the point, as it is not intended in all cases to connect the cap *D* with the finger-bar to aid in supporting the finger, for it is found that in many cases the shank of the cap affords a lodgment for grass and other obstructions, which are freely discharged when the cap is made without a shank, as shown in Fig. 6. In order to avoid crooking this neck into a form approximating the letter *S*, to prevent acute angles between the shank and finger, I have cut out the rear part of the point so as to form a space, *d*, in front of the neck, and I have also cut away the front part of the shank *b*, so as to form a space, *e*, behind the neck, which spaces, particularly as their angles are rounded and they are made widest at the lower end, prevent the binding or clogging of grass therein that would take place if the angles were left acute. Ribs *f* are formed on each side of the front part of the shank, leaving a space, *e*, between them for the descent of such matter as may enter from above, and as this space is made tapering and widest toward the bottom, any piece of matter that can find an entrance above, will easily pass through and be discharged below. The corners *i* of these ribs have acute angles to facilitate the detachment of grain, fibers, &c., from the back of the sickle-stock. The caps *D* are made concave on the under side and convex above, as shown, leaving a margin at each edge for a bearing to hold the sickle down. The concavity or arch widens and rises toward the rear end of the cap, so that, while it affords as free a discharge for grass, &c., as the open-top cap, it is free from the objection to which the open-top cap is liable of admitting obstructions from above. This cap, to produce the best effect, should be made separate from and connected with the lower part of the point by means of the improved joint secured to me by a former patent; but it may be made in one piece with the

lower part of the finger if any constructor prefers that mode of construction. My invention in this particular relates to the form of the cap, not to the manner of connecting it with other parts. The rear of this cap may have a shank, *g*, extending over the finger-bar and be fastened thereto by means of a screw or otherwise.

What I claim as my invention, and desire to secure by Letters Patent, is—

Forming the finger with an oblique neck, *e*, arranged substantially in the manner and for the purpose herein set forth.

In testimony whereof I have hereunto subscribed my name.

JOHN H. MANNY.
